UNITED STATES PATENT OFFICE.

JOSEPH SHEETS, OF GREEN BANK, WEST VIRGINIA.

RAIL-JOINT.

No. 926,297.

Specification of Letters Patent. Patented June 29, 1909.

Application filed November 11, 1908. Serial No. 462,128.

To all whom it may concern:

Be it known that I, JOSEPH SHEETS, a citizen of the United States, residing at Green Bank, in the county of Pocahontas and State of West Virginia, have invented a new and useful Rail-Joint, of which the following is a specification.

It is the object of the present invention to provide rail joints of such construction that the weight of the rolling stock traveling over the rails will act to firmly bring one rail into engagement with the other so that it will be practically impossible for the rails to become accidentally disconnected.

Broadly speaking, the invention resides in providing one of the rails to be joined, with an extension the sides of which are beveled and the end edge of which is inclined as is also that end of the rail from which the extension projects. The extension is provided with inclined locking lugs and these lugs seat in seats formed in the walls of a recess which is formed in the end of the other rail and which receives the said extension, the end wall of this recess being inclined to a degree corresponding to the angle of inclination of the end edge of the extension and the end of the second mentioned rail itself being also inclined to abut against the inclined end of the first mentioned rail when the two are assembled.

In the accompanying drawings, Figure 1 is a view in side elevation of one rail and a vertical longitudinal section of the other rail, the two rails being in position ready to be assembled, Fig. 2 is a top plan view of the rail shown in elevation in Fig. 1, and Fig. 3 is a vertical transverse sectional view through the two rails after they have been assembled.

One of the rail ends is indicated in the drawings in general by the reference character A and the other by the reference character B. The rail end A has its web increased in thickness as indicated by the numeral 5 and the end of the rail is cut at an angle or inclined upwardly as indicated by the numeral 6. This inclined end 6 of the rail A is clearly seen in Fig. 2 of the drawings, and integral with the said end of the rail and projecting therefrom in a line therewith is an extension 7. The extension 7 above mentioned is of a height to extend from the base of the rail to a plane immediately below the plane of the under side of the tread of the rail and, as in the case of the end of the rail A, and the extension thereof, has its end cut at an angle or inclined as at 8 in a plane par-

allel with the plane of the end of the rail proper. As clearly shown in the said Fig. 2 of the drawings, the extension 7 has its sides lying in upwardly converging planes, or in other words, the extension is of greater width at its base than at its upper edge, and formed upon each side of the extension is a plurality of locking lugs 9 which lugs extend obliquely and have their line of extent parallel to the angularly cut end 6 of the rail. As shown in Figs. 2 and 3 of the drawings, the lugs 9 are of the same width throughout but are increased in thickness in the direction of the base of the rail so that viewed from their edges, they appear as wedges and, as a matter of fact, perform the function of a wedge upon assembling of the rail ends. In fact, the entire extension is in effect a wedge. The web of the rail end B is also increased in thickness as indicated by the numeral 10, and this rail end is formed through its base and its extremity with a recess 11 the side walls of which converge upwardly and the end walls inclined as at 12 at the same angle with respect to the base of the rail as the inclined end 8 of the extension 7 with respect to the base of its rail. Also, the end of the rail B is cut at an angle as indicated by the numeral 13 in a plane parallel with the plane of the end walls 12 of the recess in the said rail. Each of the side walls of the recess 11 in the rail end B is formed with a plurality of seats 14 which are in the nature of recesses extending diagonally upwardly in parallel relation with respect to the angularly cut ends 13 of the said rail. The seats 14 are increased in depth in a downward direction so as to receive the locking lugs 9 of the extension 7 of the rail end A, it being understood that in assembling the rail ends, the rail end B is disposed with its base coincident with the upper edge of the extension 7 of the rail end A and with the angularly cut end 13 coincident in line of extent with the corresponding end 6 of the rail end A, and that the said rail end B is then folded downwardly in an oblique direction with the seats 14 receiving the locking lugs 9.

As heretofore stated, the entire extension 7 with its locking lugs 9 is in effect a wedge and the recess 11 in the rail end B and the seats 14 for the locking lugs 9 are so proportioned as regards their dimensions with respect to the extension 7 and its said lugs 9 that the extension will have a slight wedging reception in the recess. It will further be under-

stood that the weight of rolling stock passing over the rails will act to force the rail B downwardly into tighter engagement with the rail end A and that in this manner, the joint will always be a solid one.

What is claimed is:—

1. In a rail joint, the meeting ends of two rails, one provided with an extension having beveled sides and upwardly tapered locking lugs inclined in a direction lengthwise of the rail, the other rail being formed with an undercut recess to receive the extension of the first mentioned rail and in the walls of the recess with seats for the locking lugs of the extension.

2. In a rail joint, the meeting ends of two rails, one provided with an extension having angular upwardly tapered locking lugs inclined in a direction lengthwise of the rail, the other rail being formed with an undercut recess to receive the extension of the first mentioned rail and in the walls of the recess with inclined seats to receive the said locking lugs.

3. In a rail joint, the meeting ends of two rails, one provided with an extension having upwardly tapered locking lugs inclined in a direction lengthwise of the rail and an inclined end edge, the other rail being formed with a recess to receive the extension of the first mentioned rail, the end wall of the recess being inclined to engage with the inclined end edge of the extension of the first mentioned rail, the said walls of the recess in the second mentioned rail being formed with seats inclined in a direction lengthwise of the rail to receive the locking lugs of the extension of the first mentioned rail.

4. In a rail joint, the meeting ends of two

rails, one provided with an extension projecting from one end thereof, said end of the said rail being inclined downwardly, the extension being provided, upon its side, with downwardly inclined lugs, the other rail being formed with a recess to receive said extension of the first mentioned rail, the said end of the second mentioned rail being inclined to fit against the inclined end of the first mentioned rail when the rails are assembled, the walls of the recess being formed with seats to receive the locking lugs of the said extension.

5. In a rail joint, the meeting ends of two rails, one provided with an extension having beveled sides and inclined locking lugs and an inclined end edge, the other rail being formed with a recess to receive the said extension, having inclined walls formed with inclined seats to receive the locking lugs of the extension, the end wall of the recess in the second mentioned rail being inclined to engage with the inclined end edge of the said extension.

6. In a rail joint, the meeting ends of two rails, one provided with an extension having beveled sides and inclined locking lugs tapered in an upward direction, the other rail being formed with a recess to receive the said extension and with seats to receive the said locking lugs, the said seats being decreased in depth in an upward direction.

In testimony that I claim the foregoing as my own, I have hereto affixed my signature in the presence of two witnesses.

JOSEPH SHEETS.
